UNITED STATES PATENT OFFICE.

CHARLES P. NORTHINGTON, OF MACON, GEORGIA.

SIGNAL SYSTEM.

Application filed November 24, 1925. Serial No. 71,247.

The present invention relates to signal systems of the type in which an electrical signal is automatically transmitted from a signal station to a central receiving station 5 upon the unlawful or unauthorized entry into a residence or place of business.

More specifically it relates to signal systems of the type known as electrical burglar alarms in which the unauthorized opening of a door or window will cause a signal to be transmitted over a telephone or similar line to a central station.

It is an object of the present invention to provide an electrical signal system in which 15 the opening of a door or window will cause a signal to be transmitted to a central station, unless previous to such operation of the door or window, a safety signal is transmitted from the central station to the signal 20 location.

It is a further object of the present invention to provide a signal system for use in hotels, apartment houses, private residences, places of business or other similar 25 places, in which telephone service is available, which signal system is adapted for connection to the telephone circuit and causes a signal to be transmitted to the telephone central upon an entry not authorized 30 or previously anticipated by the party or parties in charge of the telephone central.

It is a still further object of the present invention to provide a signal system in which a signal is transmitted to a telephone 35 central station upon the entry of any person through a door or analogous structure unless prior to such entry a safety or setting signal is transmitted from the central station to the signal location.

40 In the accompanying drawings which illustrate several embodiments of the present invention,—

Figure 1 is a view of the same as applied to a door,

45 Fig. 2 is an enlarged view, partly in section, of the structure shown in Fig. 1,

Figs. 3 and 4 are section views of Fig. 2 along the section line 3—3 showing the structure in various stages of operation,

50 Fig. 5 is a sectional view of the structure taken through the section lines 5—5 of Fig. 2,

Fig. 6 is a sectional view also taken along the line 5—5 of Fig. 2 showing the device 55 in a position just subsequent to signal operation,

Fig. 7 is a view partially in section taken along the line 7—7 of Fig. 2,

Fig. 8 is a view of a modification of the invention as applied to a door structure.

Fig. 9 is an enlarged view of a portion of such structure,

Figs. 10 and 11 are sectional views taken on the section line of Fig. 8 identified as 10—10,

Fig. 12 is a section taken along the section lines 12—12 of Fig. 9,

Fig. 13 is a view partially in section of an attachment to the telephone located in the apartment or residence in which the 70 signal is employed,

Fig. 14 is a sectional view of the same taken along the lines 14—14 of Fig. 13,

Fig. 15 is a top view of this structure 75 partially in section.

In the specific embodiment of the present invention disclosed in Figs. 1 to 7 inclusive, the device comprises a recessed cabinet 1 located adjacent to a door or similar closure device 2. The cabinet 1 is provided with a small door 3 which is provided with a lock 4. The cabinet is of sufficient size as regards depth and height to contain an electrical switch mechanism 5. As indicated in the specific embodiment, this switch structure consists of the switch contact portions of a standard desk telephone with the base and mouth-piece removed. If desired, however, the cabinet or compartment 1 may be made of sufficient size to accommodate a desk telephone in its entirety in which case the cabinet 1 and its associated structure not only functions as a burglar alarm or signal system but in addition the same provides a place in which a telephone may be located 95 and locked against unauthorized use.

Located on the door 3 of the compartment in a position closely adjacent to the opening edge of the door 2 is a closure or shallow box 6. This box has a door 7 of spring snap construction which has a projection 8 which extends over and beyond the jamb of the door 2. Located on the inner side of the door 2 inset into its edge is a spring latch structure 9. This spring latch structure has a projecting latch member 10 which upon the opening of the door from the outside, contacts with the projection 8, thereby opening the door 7 of the shallow box 6. The spring latch structure 9 is provided with a knob 11 on the inside of the door which knob may be operated to withdraw the 110

latch 10 from operative position so that by proper manipulation of this knob the door 2 may be opened from the inside without causing the door or lid 7 of the shallow box 6 to spring open.

The switch or signal structure, previously referred to, has the well known hook or receiver arm 12. Fastened to this portion of the structure in any suitable manner is a flexible cord or element 13 carrying at its lower end or extremity a ball 14. The top of the shallow box 6 has a notch 15. Just above the notch 15 is located a diagonal hole or opening 16 of sufficient size to permit the ball 14 to pass readily therethrough and the cord or flexible element 13 is of such length and the proportions of the structure just recited are such that when the switch lever 12 is in its normal up-position, the ball 14 will be pulled up into or through the opening 6 into the position shown in Fig. 4 of the drawings.

In order to place the device in operation for the transmission of a signal the door 1 of the compartment is unlocked and opened, 25 and the ball 14 pushed downwardly through the diagonal orifice 16. The ball is then pulled down and placed in the shallow box 6, the cord or flexible element 13 being accommodated in the slot 15 cut in the top of the box. It will therefore be noted that when the door 2 is opened from the outside the latch 10 contacts with the projecting member 8 on the lid 7 of the shallow box 6, 35 thereby causing the same to snap open. This causes the release of the ball 14 as the notch 15 is only of sufficient depth to accommodate the flexible element 13. The ball being released, the same is withdrawn 40 into the interior of the compartment through the diagonal opening 16, and the hook member 12 being normally biased to signaling position, the same operates to transmit a signal through the electrical telephone circuit or similar circuit with which the switch structure 5 may be associated.

In some instances in which this specific embodiment just described may be used, the door 2 might be provided with a transom. 50 In installations of this character a guard structure 17 projecting over and beyond the shallow box 16 and covering the diagonal orifice 16 is provided. This guard renders it impossible for a burglar or person even fully acquainted with the operation of the signal device, to reach through the transom and by means of a stick or wire to hold the ball 14 in order to restrain the same from passing through the orifice 16 and permitting 55 the signal to be given.

A pin or latch member 18 is located immediately above the top of the shallow box 6. This latch has a free lateral motion through the staples 19 and its outer end has 60 a cut-away portion 20 of such size that when

the latch member 18 is moved to the right the cut-away portion engages with the flexible cord or element 14 at the point where the same passes through the notch 15. By the movement of this latch to the right, the flexible element is engaged between the cut-away portion 20 and the slot 15 and the ball 14 is therefore incapable of release when the door 2 is opened. In order to move or operate the latch 18 laterally into this safety position an electrical bell or buzzer structure 21 is mounted upon the exterior of the door 3 of the cabinet 1. This bell or buzzer structure has its clapper 22 closely adjacent the end of the latch member 18 and when 65 this ball or buzzer is operated the impulses of the clapper 22 against the end of the member 18 will shift the same to the right and into the safety position.

While the buzzer or bell structure 21 is 70 illustrated as being on the outer surface of the cabinet door 3, it is possible to locate the same within the cabinet and to have the clapper project through the door adjacent to the outer end of the latch member 18. The 75 electrical bell or buzzer structure 21 is of the usual telephone ringer type although any suitable electrical buzzer or bell structure may be utilized.

In the specific embodiment under description, this bell or buzzer structure is connected into the telephone circuit so that when the central operator gives a ringing signal on the circuit into which the electrical signal device is connected the latch 18 will 80 be moved to the safety position by such ringing impulse.

The operation of the specific embodiment thus described is as follows: The authorized occupant of the room or dwelling upon going out will set the signal by unlocking the door 3 of the cabinet 1 and placing the ball 14 in the shallow box 6, subsequently closing the lid 7. If the latch 18 is in the safety position, it is also moved to the left or operative position. The occupant of the room or dwelling then notifies the central operator or switch board operator that he is leaving his room or dwelling. The switch board operator will thereupon make a notation 95 that such room or dwelling is vacant. If she receives a signal on the signal lamp of the board she will at once answer "operator", or "number, please", and if she receives no immediate response over the telephone she will be aware that an unlawful or unauthorized entry has taken place and she will at once call the attention of the house detective or the police to this fact, giving them the number of the room or the location 100 of the dwelling, as the case may be.

If the signal device is located in an apartment or hotel, the authorized occupant of the room will upon his return identify himself at the desk to the operator who will there- 105

upon impress a ringing signal upon the telephone circuit associated with his room or apartment, thereby setting the safety latch 18 and permitting the authorized occupant 5 to enter his room or apartment without causing the signal device to operate.

Where there is a telephone in the room or apartment incorporated in the same circuit with the signal device or switch and where 10 the burglar or unauthorized party might be entirely conversant with the operation of the protective system, herein described, it would be possible for such person to proceed at once to the telephone after making 15 an unauthorized entry and to satisfactorily answer the operator's inquiry of "operator" or "number, please".

In order to prevent this, I have provided in conjunction with the other elements of 20 the signal system a structure for preventing such action from taking place. In order to do this I provide, as shown in Fig. 13, a felt or cork disk 23 which may be inserted as a sound proof plug in the telephone 25 mouth-piece. This plug or disk is provided with a loop 24. Through the center of this loop is passed a retaining bolt or member 25, the same passing through drilled holes 26 and 27 formed at the proper location in 30 the telephone mouth-piece. This bolt is threaded at its outer end 28 and a small nut 29 is screwed upon these threads.

When the authorized occupant of the room leaves he places the plug or disk 23 in position as indicated in Figs. 13 to 15 inclusive, after having notified the telephone operator of his departure. Upon the unauthorized 35 entry of a person into the room or apartment, it would be necessary for such person to 40 first unscrew the nut 29 from the bolt 28 in order to remove the sound proof-disk 23. This would take such a time interval that the operator at the switch board not receiving any response to her inquiries would have 45 become conversant immediately with the fact that an unlawful entry had been made and she would immediately notify the detective or police in the manner hereinbefore described.

50 Instead of using a nut 29 threaded upon the bolt 28, it would of course be possible to pierce a hole through the extremity of the bolt 28 and to use a small padlock with the hasp passing through this hole. Such structure would of course prevent unauthorized use of the telephone, but it should be understood that it is not necessary to provide unauthorized use of the phone, delayed use being entirely sufficient in the present instance.

55 In the modification shown in Figs. 8 to 12 inclusive, a small cabinet or compartment 30 is provided adjacent the door 2 or similar closure device. This cabinet contains a telephone 31. Located below this cabinet and 60 on the inside wall is a spring hinge 32 biased

to closed position, as shown in Fig. 11. The outer or free end of this hinge has an extended portion 33 which engages a spring holding clip 34 which functions to hold the same in open position. When the hinge is 70 in this position, the tip of the projection 33 extends beyond the jamb of the door in such position that the spring latch 10 acts to remove the portion 33 from the spring clip 34 and will thereby cause the spring hinge to assume its normal biased closed position, 75 shown in Figure 11. A knob 11 on the inner side of the door provides means for withdrawing the latch 10 from operative position when opening the door from the inside. 80

Immediately below the recess 30 is located a smaller recess 35. Projecting into this recess, through the inner end of the spring is a button 36 having a right angle projection 37 at its rear end. A tubular opening or 85 passageway extends between the compartment 30 and the compartment 35, this passageway extending vertically and being located above the button projection 37. Extending through this passageway is a cord or 90 flexible element 38 connected to the receiver hook of the phone 31. This cord is fastened at its lower end to a ball or similar enlarged member 39, and the cord and association of parts or members are such that when the ball 95 39 is pulled down below the projection 37 and the button 36 is withdrawn, the receiver hook of the telephone is held in the down or non-signal position. The telephone receiver 40 may thereupon be lifted from the 100 hook without causing a signal to be given to the operator.

In order to set the device as described in the previous paragraph, the lower compartment 35 may be provided with a suitable 105 door 41 which may be opened for this purpose and which may be locked in a closed position by a suitable lock 42 after the device has been set.

In operation, when the door 2 is opened 110 from the outside the spring latch 10 carries the projection 33 out of the spring holding clips 34, and the free portion of the spring in returning to closed position hits against the button 36 driving the same into its inner position as shown in Fig. 11 and releasing the ball or enlarged member 39. The receiver hook thereupon lifts under its normal spring action and gives a visual signal on the telephone switch board to the operator. 120 As the door 43 may have a suitable lock mechanism 44, the telephone is rendered inaccessible and no response can be given to the inquiries of the telephone operator.

In a modification of the character de- 125 scribed it may be desirable to construct the cabinet or compartment 30 of sufficient size to contain a small phonograph adjacent to the telephone 31. The flexible element 38 would then be connected to the starting lever 130

of the phonograph as well as the telephone receiver hook, so that upon its release, it would start the phonograph simultaneously with the movement of the hook into signalling position, a suitable record would be carried on the disk or cylinder of the phonograph, which thus set in motion adjacent the telephone, would give a vocal signal to the telephone operator at the switch board.

10 In the foregoing specification, it should be understood that while the specific embodiments are described in connection with a door, the invention is equally applicable to any closure device such as a window, transom, etc.

The specific embodiments described are given by way of illustration only and it should be understood that the invention is susceptible of various other embodiments 20 within the scope of the claims appended hereto.

What I claim is:

1. In a signalling device, the combination of a wall cabinet, a door for said cabinet, a box on said door, a cover for said box, a circuit closing device within said cabinet, and means for holding said circuit closing device in inoperative position when located within said box.

20 2. In combination with a closure device, a wall cabinet located adjacent thereto, a circuit closing device located within said cabinet, means for holding said circuit closing device in inoperative position, a latch mechanism for releasing said means mounted on the closure device, and an electrically actuated safety device for rendering said means inoperative by said latch mechanism.

3. In combination with a closure device, a wall cabinet located adjacent thereto, a circuit closing device located within said cabinet, a door for said cabinet, means mounted on the exterior of the door for holding said circuit closing device in inoperative position and a latch mechanism for releasing said means mounted on the closure device.

4. In combination with a closure device, a wall cabinet located adjacent thereto, a circuit closing device located within said cabinet, a door for said cabinet, means mounted on the exterior of the door and including a box and cover for holding said circuit closing device in inoperative position, a latch mechanism mounted on the closure device for opening said cover.

5. In combination with a closure device, a wall cabinet located adjacent thereto, a circuit closing device located within said

cabinet; a door for said cabinet, a flexible element extending from said circuit closing device through a diagonal passageway in said door, a box mounted on the exterior of the door, an enlarged rigid element carried on the end of said flexible element and adapted to be placed within said box, a cover to said box for retaining said rigid element therein, and a latch mechanism mounted on said closure device for opening said cover.

6. In combination with a closure device, 70 a wall cabinet located adjacent thereto, a telephone circuit closing device located within said cabinet, a door for said cabinet, a flexible element extending from said circuit closing device through a diagonal passageway in said door, a box mounted on the exterior of the door; a curved guard located above said box and the exterior end of said passageway, an enlarged rigid element carried on the end of said flexible element and adapted to be placed within said box, a cover to said box for retaining said rigid element therein, and a latch mechanism mounted on said closure device for opening said cover when said closure device is operated.

7. In a signal system adapted for use with a telephone line and an instrument, the combination of a closure device; a wall cabinet located adjacent thereto, a circuit closing device intercalated in said telephone line and located within said wall cabinet, a sound proof plug for temporarily obstructing the mouth piece of said telephone instrument and retaining means therefor requiring a time consuming operation for its removal.

8. In combination with a closure device having an inner and outer side, a wall cabinet located adjacent thereto, a telephone circuit closing device located within said cabinet, a door for said cabinet, means for preventing unauthorized opening of said door, a flexible element extending from said circuit closing device through said door, a box mounted on the exterior of the door, an enlarged rigid element carried on the end of said flexible element and adapted to be placed within said box, a cover to said box for retaining said rigid element therein, a latch mechanism mounted on said closure device for opening said cover and releasing said rigid element when said closure device is opened, and means located on the inner side of said closure device for withdrawing said latch mechanism to an inoperative position.

In testimony whereof, I have hereunto affixed my signature.

CHARLES P. NORTHINGTON.
